United States Patent Office

Des. 195,986
Patented Aug. 13, 1963

195,986

STIRRING ROD

James H. Ogg, North Hollywood, Calif., assignor to Zoo-Piks, North Hollywood, Calif., a partnership

Filed Apr. 30, 1963, Ser. No. 74,681

Term of patent 14 years

(Cl. D44—29)

Fig. 1

Fig. 2

Fig. 3

Fig. 4

FIGURE 1 is a side view of a stirring rod showing my new design;

FIGURE 2 is a front view thereof;

FIGURE 3 is a side view of the side opposite that in FIGURE 1; and,

FIGURE 4 is a rear view thereof.

I claim:

The ornamental design for a stirring rod, substantially as shown.
